Patented Sept. 14, 1976

241,424

COMBINED VEHICLE ELEVATING ROOF AND ENCLOSURE UNIT

David Lee, Northchurch House, Northchurch,
Hertfordshire, England

Filed Apr. 17, 1975, Ser. No. 568,801

Term of patent 14 years

Int. Cl. D12—16

U.S. Cl. D12—156

Fig. 1.

Fig. 2.

Fig. 3.

Fig. 5.

Fig.4.Fig.6.FIG. 1 is a side elevational view of a combined vehicle elevating roof and enclosure unit showing my new design in open condition;

FIG. 2 is a perspective view thereof taken from one end and the side opposite to that shown in FIG. 1;

FIG. 3 is a side elevational view thereof opposite to that shown in FIG. 1;

FIG. 4 is a top perspective view thereof in closed condition;

FIG. 5 is an end elevational view thereof; and

FIG. 6 is a perspective view thereof taken from the end opposite to that shown in FIG. 5.

I claim:

The ornamental design for a combined vehicle elevating roof and enclosure unit, as shown and described.
